(57) **CLAIM**

The ornamental design for a tableware set, as shown and described.

DESCRIPTION

FIG. 1 is a top, front, right side perspective view of a bowl of the tableware set, showing my new design;

FIG. 2 is a bottom, rear, left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a top, front, right side perspective view of a plate of the tableware set, showing my new design;

FIG. 10 is a bottom, rear, left side perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof;

FIG. 17 is a top, front, right side perspective view of another plate of the tableware set, showing my new design;

FIG. 18 is a bottom, rear, left side perspective view thereof;

FIG. 19 is a front elevational view thereof;

FIG. 20 is a rear elevational view thereof;

FIG. 21 is a left side elevational view thereof;

FIG. 22 is a right side elevational view thereof;

FIG. 23 is a top plan view thereof;

FIG. 24 is a bottom plan view thereof;

FIG. 25 is a top perspective view of the tableware set including the bowl and two plates; and,

FIG. 26 is a bottom perspective view thereof.
